UNITED STATES PATENT OFFICE.

ARTHUR A. DAY, OF BUFFALO, NEW YORK, ASSIGNOR TO BUFFALO FORGE COMPANY,
OF BUFFALO, NEW YORK.

AIR WASHER AND THE LIKE.

1,402,147.

Specification of Letters Patent. Patented Jan. 3, 1922.

Application filed September 18, 1919. Serial No. 324,652.

To all whom it may concern:

Be it known that I, ARTHUR A. DAY, a citizen of the United States, residing at Buffalo, in the county of Erie and State of New York have invented a new and useful Improvement in Air Washers and the like, of which the following is a specification.

This invention relates to air washers, humidifiers, or analogous apparatus by which air or other gas is caused to contact with water or other liquid for washing or otherwise treating or conditioning the air or gas by contact with the liquid. A well-known type of apparatus of this nature for washing and altering the humidity of air comprises a casing through which a current of air passes and in which it is brought into intimate contact with water, which may be discharged in a fine spray into the casing, and an eliminator or separator consisting of spaced plates of zig-zag or other suitable form arranged and spaced to form tortuous passages through which the moisture-laden air passes so that the free particles of liquid are removed from the air by reason of their contact with the surfaces of the eliminator plates. These eliminators usually consist of a multiplicity of relatively large, closely arranged plates so that if the eliminator is completed with the plates in position at the factory it constitutes a cumbersome, heavy piece of apparatus which is expensive to pack and ship. Furthermore, a considerable amount of skilled labor by experienced workmen is required, both at the factory in assembling and permanently connecting the parts of the eliminator and at the place where it is to be installed, in properly setting the eliminator in the apparatus and making proper joints and connections. When the apparatus is thus constructed with the eliminator plates permanently secured in position, it is very difficult and practically impossible to properly clean the plates and paint them, which should be done from time to time to preserve the plates, and it is a very expensive and laborious matter to remove the plates for repairs or to renew old plates.

One of the objects of this invention is to produce an apparatus of the sort mentioned which is of a knock-down construction, or composed of separate parts or units which can be readily manufactured, handled and

shipped and can be properly assembled or set up expeditiously with the minimum of expense and skilled labor.

Other objects of the invention are to construct the eliminator so that the eliminator plates are detachably or removably held in place in the apparatus, thus enabling any one or more of the plates to be readily removed for cleaning or painting, or to enable the replacement of a defective plate or plates; also to construct the eliminator so that the several plates of the same can be packed compactly and shipped in a knock-down nested condition to reduce the shipping expense, and so as to ensure of being properly mounted or placed in the apparatus, without possibility of mistakes in setting up the apparatus by reason of the use of unskilled workmen; and also to improve apparatus of this sort in the other respects hereinafter described and set forth in the claims.

In the accompanying drawings:

Fig. 1 is a transverse sectional elevation on line 1—1, Fig. 2, of an air washer embodying the invention.

Fig. 2 is a fragmentary longitudinal sectional elevation thereof, on line 2—2, Fig. 1.

Fig. 3 is a fragmentary sectional plan view thereof on line 3—3, Fig. 2, on an enlarged scale.

Fig. 4 is a perspective view of the fastening means for one of the holding bars for the eliminator plates, showing the parts disconnected.

Fig. 5 is a sectional elevation showing one of the plate-holding bars and its fastening means connected.

A represents the casing of the apparatus. Usually the casing is of rectangular cross-sectional form, open at its opposite ends for the entrance and discharge of the air, and is constructed so that its lower portion forms a receiving tank or reservoir for the water or liquid with which the air or gas is treated. This casing can be of any usual or suitable construction but it is preferably made of sheet metal and so that it can be built and shipped in sections and the sections readily set up and connected at the place where the apparatus is to be installed. As shown, the casing comprises a lower horizontal portion or section B which forms a tank or reser-

voir in the lower portion of the casing, and a main or upper portion which surmounts the water tank and is composed of separable opposite side walls C and a top D, 5 which are bolted or otherwise suitably secured together so that the walls can be shipped knock-down and assembled at the job.

E represents the eliminator for removing 10 or separating the free particles of water or liquid from the air or gas. The eliminator shown consists of a multiplicity of upright parallel zig-zag plates 10 arranged relatively close together and separated by tortuous passages 15 for the air. As is well known, the eliminator is located in the casing so that the air or gas, after passing through the liquid spray from spray nozzles (not shown), or being otherwise brought into contact with the liquid, passes through the tortuous passages between the eliminator plates for separating the free liquid from the air or gas. The eliminator plates rest at their lower ends upon a suitable support in the washer casing. 20 This support preferably consists of opposite parallel angle bars 11 and 11^a which extend horizontally across the casing and are preferably supported above the bottom of the tank B by suitable legs or stands 12 25 which, in the construction shown, consist of metal bars bent into substantially inverted U-form and having inturned lower ends forming feet. One of the bars, 11, is preferably bolted or otherwise stationarily secured on the legs or stands 12 and connects the same. The other bar, 11^a, preferably rests loosely on the legs or stands 12 between the opposite walls of the casing A and is removable retained in place on the stands by suitable means, such, for instance, as turn buttons or plates 13 pivoted to the stands 12 and adapted to be turned to and from an upright holding position in which the upper ends of the buttons project up in front of the removable bar 11. The eliminator plates 30 rest on the bars 11, 11^a between their upturned flanges, and are held in the intended parallel, spaced relation by holding bars or members 14 and 15 which extend across the casing at opposite sides of or in front and in rear of the group of eliminator plates. These bars are preferably arranged in pairs and any suitable number of pairs of the bars 35 may be employed as may be necessary, depending upon the size of the eliminator, so as to hold the eliminator plates rigid. In the construction shown, three pairs of these bars are used, one pair near the upper ends of the eliminator plates and the remaining two 40 pairs at suitable points intermediate the ends of the plates. The bars 14 at one side of the eliminator, preferably the rear side, do not have to be removed and, if desired, they can be permanently secured in the casing. Preferably, however, these bars 14, with the ex-

ception of the top one, are removably secured in place in the same way as the front bars 15, which will be presently described. The top bar 14 shown is of Z-form and has an upper flange which is soldered or otherwise secured to the top wall of the casing. The bars 15 at the front or opposite side of the eliminator are removably secured in the casing, preferably as follows:

Each bar 15, which may be of any suitable shape but is preferably an angle bar, 75 rests at its opposite ends upon and interlocks with two brackets or supports 17 which are permanently secured to and project inwardly from the opposite side walls C of the casing. 80 Each of these brackets 17 consists of a bent metal plate having oppositely projecting end portions 18 which are riveted or otherwise secured to the casing wall, and upright parallel portions 19 which project inwardly 85 from the wall of the casing. These inwardly projecting portions 19 are spaced apart and form a socket adapted to receive the depending vertical flange of the bar 15. The upper portion of the bent inner end of the 90 bracket is removed, thus leaving the upper parts of the portions 19 disconnected and the lower parts thereof joined by an end wall 20. The vertical flange of the bar 15 is provided 95 near each end with a downwardly opening vertical slot 21. When the vertical flange of the bar 15 is slipped downwardly into the sockets or spaces between the portions 19 of the two opposite brackets, the slots 21 in the flange receive the end walls 20. The bars 15 100 are thus held securely and rigidly in place and the opposite side walls of the casing are connected or tied together by the bars. Nevertheless the bars can be readily removed by lifting them upwardly to disengage their ends 105 from the brackets 17. The rear bars 14 are preferably removably secured in place in the same way, so as to standardize the construction and enable the parts of the apparatus to be more readily assembled. The 110 brackets are permanently secured in proper position on the side walls at the factory, and in setting up the apparatus it is only necessary to engage the bars 14 and 15 with the brackets. This ensures the proper placing 115 of the parts and no tools are necessary to secure and remove the bars.

The inwardly projecting horizontal flanges of the opposite bars 14 and 15 are provided with seats or parts by which the front and rear edges of the eliminator plates are held. These seats, which are preferably formed by notches 22 in the edges of the bars, are uniformly spaced at the required distance to give the desired spacing of the eliminator plates 10 and they thus serve to uniformly space the eliminator plates and retain them accurately in position. In assembling the eliminator, the eliminator plates are placed with their lower ends resting on the sup- 125 130

porting bars 11 and 11^a and with their rear edges entering the notches 22 in the rear bars 14. The removable front bars 15 are then engaged with the front edges of the 5 eliminator plates and driven into place in their sockets or brackets 17. The eliminator can be thus quickly set up in position in the washer casing and the plates will be accurately and properly spaced and retained in 10 position without requiring any particular skill on the part of the workmen in setting up the apparatus and no solder or rivet joints have to be made. If it is desired to remove any plate or plates of the eliminator 15 for cleaning, painting or renewing the same, this can be readily done by removing the loose supporting bar 11^a and disengaging the front bars 15 from their brackets 17. Any one or more of the eliminator plates 20 can then be readily moved forwardly out of engagement with the rear holding bars 14. Preferably the front and rear bars 14 and 15 of the intermediate pairs are connected by bolts 23 which extend through holes 25 or slots in the vertical flanges of the bars and are provided with removable nuts 24 at their front ends. Each of the bolts passes through holes in one of the eliminator plates, the inclined portions of which intersect the bolt. When the nuts 24 are loosened, the removable front bars can be disengaged from their securing brackets 17. The bolts 23 tie the front and rear bars 14 and 15 together and prevent them from sagging and 30 from disengagement from the edges of the eliminator plates. All of the eliminator plates are therefore rigidly tied together and held in place, and the bars connecting the plates between their ends prevent them 35 from rattling or vibrating and making an objectionable noise.

In the apparatus described the eliminator plates are arranged vertically and the invention has been described in connection 40 with such an arrangement. In some apparatus, however, the eliminator plates are differently arranged, for instance horizontally and obliquely, and the invention is equally applicable to these different arrangements, the holding bars engaging the edges of the plates and acting in the same manner to space and secure the plates. It is not intended therefore to restrict the invention to 45 the vertical arrangement shown. Obviously 50 also, the removable holding bars can be removably secured in place in other ways.

25, Fig. 3 represents an upright bar or dam which is secured to one of the side walls C of the washer casing and extends inwardly therefrom to the adjacent eliminator plate, having its inner upright edge seated in one of the angles of the eliminator 55 plate. This bar 25 is for the purpose of preventing the air from blowing water through the casing between the side wall

and the adjacent eliminator plate. The bar preferably has a forwardly-bent, inner edge 26 which prevents the escape of the water past the same. This bar can be permanently riveted or secured to the side wall of the 70 casing at the factory and removes the necessity for soldering or otherwise securing the ends of the first eliminator plate to the side wall of the casing, or making other provision to prevent the escape of the water, as 75 has been heretofore customary. One of these dams is used at each end of the eliminator.

In the washer shown, the upper front corners of the eliminator plates are cut off at an angle to enable water from nozzles 27 arranged in the upper portion of the casing to be discharged against the upper ends of the eliminator plates for the purpose of flushing a portion of the inclined faces of the plates and causing films of water to flow downwardly on these faces to keep the plates clean and free from accumulations. The pipe 28 carrying these nozzles, in the construction shown, is arranged behind a shield which extends downwardly from the top 80 wall of the casing to a point below the cut-off upper corners of the eliminator plates. This shield preferably has short, fixed end 85 portions 29 and a movable intermediate portion or door 30 which is hinged at its lower edge to the upper removable plate-holding bar 15. The free upper end of this hinged section is adapted to be secured by thumb screws, or other fastenings, to the top of the washer casing. The hinged section can 90 thus be released and swung down to afford access to the spray nozzles 27 and can be removed with the bar 15 from the casing. The fixed end sections are secured in place 95 by rivets or the like passing through end 100 flanges on the sections and through holes provided for them in the side walls of the casing, this construction enabling the shield to be readily mounted in the casing when the parts thereof are assembled. 110

32 and 33 represent two overlapping plates secured on the under side of the top of the casing and having downturned rear edges or flanges which prevent the escape of water through the eliminator on the under surface 115 of the casing top. The flange of the plate 32 also forms a stop or jamb for the hinged shield.

I claim as my invention:

1. In an apparatus of the kind described, 120 the combination of a casing, a group of separate eliminator plates, and means for removably securing said plates in spaced relation in the casing to form tortuous passages, comprising a support on which said plates loosely rest, a member which releasably engages and holds one edge of each plate, a bar which is removably secured in the casing and has portions for removably engaging corresponding edges of the several 125

plates, and a bolt extending transversely from said holding member to said bar and tying said member and bar together.

2. In an apparatus of the kind described, 5 the combination of a casing, a group of separate eliminator plates, and means for removably securing said plates in spaced relation in the casing to form tortuous passages, comprising a support on which said plates 10 loosely rest, a member which releasably engages and holds one edge of each plate, a bar which is removably secured in the casing and has portions for removably engaging corresponding edges of the several plates, 15 and a bolt connecting said plate-holding member and said bar, said bolt passing through an adjacent plate, whereby said plate-holding member, said bar and said plates are rigidly tied together.

- 20 3. In an apparatus of the kind described, the combination of a casing, a group of separate eliminator plates, and means for removably securing said plates in spaced relation in the casing to form tortuous passages, 25 comprising holding means which extend crosswise of said group of plates and have portions which engage the edges of all of the plates, and means for removably securing in place a portion of said holding means, where- 30 by the same can be removed to permit the independent removal of said plates.

4. In an apparatus of the kind described, 35 the combination of a casing, a group of separate eliminator plates, and means for removably securing said plates in spaced relation in the casing to form tortuous passages, comprising a means at one side of said group of plates by means of which adjacent edges of all of the plates are releasably held, and a 40 movable device which engages and releasably holds adjacent edges of said plates at another side of said group of plates, whereby upon disengagement of said movable device from said plates independent removal 45 of any of said plates is permitted.

5. In an apparatus of the kind described, 50 the combination of a casing, a group of separate eliminator plates, and means for removably securing said plates in spaced relation in the casing to form tortuous passages, comprising a member at one side of said group of plates which releasably engages and holds the adjacent edges of all of the plates between the ends thereof and a bar which is 55 removably secured in the casing at another side of the group of plates and has portions which releasably engage and hold the adjacent edges of the plates between the ends thereof.

- 60 6. In an apparatus of the kind described, 55 the combination of a casing, a group of separate eliminator plates, and means for removably securing said plates in spaced relation in the casing to form tortuous passages, comprising a support on which said plates

loosely rest, a member which releasably engages and holds one edge of each plate, a bar which is removably secured in the casing and has portions which releasably engage corresponding edges of the several plates, 70 and means for tying said plate-engaging member to said removable bar.

7. In an apparatus of the kind described, 75 the combination of a casing, a group of separate eliminator plates, and means for removably securing said plates in spaced relation in the casing to form tortuous passages, comprising a support on which said plates loosely rest, a member at one side of said group of plates which releasably engages 80 and holds the adjacent edges of the plates, a bar which is arranged at another side of the group of plates and has portions which releasably engage and hold the adjacent edges of the plates, and fastening devices secured 85 to the casing and releasably engaging said bar to removably secure the same in place.

8. In an apparatus of the kind described, 90 the combination of a knock-down casing having separable walls, a group of separate eliminator plates, and means for removably securing said plates in spaced relation in the casing, comprising a member at one side of the group of plates which releasably engages 95 and holds the adjacent edges of the plates, a bar which is arranged at another side of the group of plates and has portions which releasably engage and hold the adjacent edges of the plates, and fastening devices which are secured to opposite walls of the casing 100 and with which said bar releasably interlocks to removably secure said bar in place.

9. In an apparatus of the kind described, 105 the combination of a casing, eliminator plates arranged in spaced relation in said casing to provide tortuous passages through which air or gas is adapted to flow for separating entrained liquid from the air or gas, and a dam secured to a wall of the casing and having a free end projecting therefrom 110 toward the adjacent eliminator plate, said free end of the dam being formed with a forwardly bent angular portion adapted to bear against the surface of the adjacent eliminator plate for preventing the passage of liquid 115 past the eliminator between said wall and the eliminator plate.

10. In an apparatus of the kind described, 120 the combination of a knock-down casing having separable walls, a group of separate eliminator plates, a bar extending crosswise of said plates and engaging the same to hold the plates, means for removably securing said bar in the casing, means for flooding the eliminator plates, and a hinged shield 125 attached to said removable bar and adapted to be fastened in a position in front of said flooding means.

11. In an apparatus of the kind described, 130 the combination of a casing, a group of sepa-

rate eliminator plates, and means for removably securing said plates in spaced relation in the casing, comprising a member at one side of the group of plates which releasably engages and holds the adjacent edges of the plates, a bar which is arranged at another side of the group of plates and has portions which releasably engage and hold the adjacent edges of the plates, brackets secured to opposite walls of the casing, and interlocking portions on said brackets and on the ends of said bar, whereby said bar is removably secured to said brackets.

12. In an apparatus of the kind described, the combination of a casing, a group of separate eliminator plates, and means for removably securing said plates in spaced relation in the casing, comprising a member at one side of the group of plates which releasably

engages and holds the adjacent edges of the 20 plates, a bar which is arranged at another side of the group of plates and has portions which releasably engage and hold the adjacent edges of plates, said bar having a pair of slots in its lower edge adjacent its ends, 25 a pair of brackets secured to opposite walls of the casing, each of said brackets having a pocket adapted to receive an end of said bar, and an end wall portion adapted to enter the adjacent slot in said bar, whereby 30 said bar is removably secured to the walls of the casing.
